CLAIM

The ornamental design for an object retrieval device, as shown and described.

DESCRIPTION

FIG. 1 is a front perspective view of an object retrieval device showing my new design.

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof; and,

FIG. 8 is a back perspective view thereof.

The broken lines shown in the figures represent portions of the object retrieval device that form no part of the claimed design.
